CLAIM

The ornamental design for a buckle member for bags, as shown and described.

DESCRIPTION

FIG. 1 is a perspective view of a buckle member for bags showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along line A-A in FIG. 2; and,

FIG. 9 is a perspective view of the buckle member for bags shown with environmental subject matter.

The broken line showing of a male buckle member in FIG. 9 depicts environmental subject matter that forms no part of the claimed design.

1 Claim, 9 Drawing Sheets
